UNITED STATES PATENT OFFICE

2,634,505

CALIPER

Howard Dewey Petch, Greenfield, Mass., assignor
of twenty-five per cent to Lawrence W. Skinner,
Chicopee, and ten per cent to Charles Bungay,
Greenfield, Mass.

Application May 26, 1950, Serial No. 164,586

1. Claim. (Cl. 33—148)

1

My invention relates to improvements in calipers used to measure internal and external diameters or calibers of cylindrical pieces and is directed more particularly to the provision of a type of single instrument which can serve for obtaining both internal and external measurements as desired.

The principal object of my invention is directed to provide a novel and improved construction in calipers consisting in precision caliper arms having adjustable caliper fingers which may serve to obtain both outside and inside measurements as may be desired, and there is the further provision of a unique construction which will eliminate the now present objectionable inconveniences, same being one which will operate with a maximum amount of ease and with a minimum degree of effort.

One of the primary purposes of my invention is to provide structural and operational improvements in devices of the class to which reference has been made, which improvements not only simplify the structure as such but also provide important distinct advantages in strength, durability and the like.

With the above primary object in view, it is another object of my invention to provide a construction of the above described character in which the number of operating parts is greatly reduced and which is compact in accordance with the demands and desires of purchasers as well as of manufacturers and which is not only distinctive in its appearance and practical in its value but also reliable in its operation and efficient in its use.

It is a still further object to provide a device which is constructed of relatively simple parts, same being adapted to be readily assembled and which, when once assembled, are positively and securely retained in operative relationship.

Other prime objects of my invention include: first, the provision of a simplified construction and arrangement of parts in calipers which is strong, durable and compact in its structure; second, the securing of a higher degree of accuracy in the manner of work performed therewith than has heretofore been possible with prior devices known in the art; third, the attainment of a flexibility or a capability of easy adjustment by which a large variety of work can be produced by means of the same device; fourth, the achievement of a greater ease in adjustment and repairs; fifth, the provision of an improved caliper which may be made more economically and with fewer operations in the manufacture of its parts, as

2

well as in the assembly of the same, than prior devices known in the art; and sixth, the provision of such other improvements in and relating to calipers of the type above referred to as are hereinafter described and claimed.

My invention also consists in certain new and original features of construction and combination of parts hereinafter set forth and claimed in conjunction with the annexed drawings which illustrate a certain form of embodiment thereof, which form is deemed preferable and is a specific disclosure for the purpose of illustrating a single embodiment of the invention by way of an example since the same has been found in practice to give satisfactory and reliable results. It is to be understood, however, that the various parts of which the invention consists can be variously changed within the scope of the appended claim without departing from the broad aspects and spirit of the invention and that the invention is not to be limited to the precise arrangement and organization of the instrumentalities as herein shown and described.

All of the above cited objects I accomplish by means of such structure and relative arrangement of parts thereof, as will fully appear by a perusal of the description below and by various specific features which will be hereinafter set forth. To these above and other ends and with the foregoing and various other and ancillary features and advantages and other objects of my invention as will become more readily apparent as the description proceeds, my invention consists in certain novel features of construction and in the combination and arrangement of parts as will be hereinafter more particularly pointed out in the claim hereunto annexed and more fully described and referred to in connection with the accompanying drawings wherein:

40. Fig. 1 is a top plan view of the device of my invention;

Fig. 2 is a side elevational view of the device shown in Fig. 1; and

Fig. 3 is a top plan view of a pair of external caliper fingers which are interchangeable with the internal caliper fingers shown in Figs. 1 and 2.

In the following description and claim, various details will be identified by specific names for convenience. These names, however, are intended to be as generic in their application as the art will permit.

Referring now to the drawings more in detail in which similar characters of reference indicate corresponding parts in the several figures, and referring more particularly to the preferred form

of my invention selected for illustrative purposes, I have shown a housing or body 4 having a pair of outwardly extending spaced apart arm members 6 and 7 extending from a side thereof, as shown in Fig. 1.

A central bore 8 extends through the body 4 and is adapted to receive a protruding neck member 10 of an indicator generally indicated by the numeral 12 and including, in addition to the aforementioned neck member 10, an indicator body member 14, a dial 15, a crystal 16, a bezel 17 and a pointer 18. The indicator 12 is of the well known construction.

The neck member 10 has an outermost end portion 20 from which outwardly extends the conventional indicator contact face 22, as shown in Fig. 1.

A set screw 24 extends through the body 4 and may be adjusted so as to firmly hold the neck member 10 relative the body 4 in any desired position.

The arm member 6 is provided with a slot 30 extending transversely therethrough in which one extremity of a lever arm 32 is held in pivotal relation with the arm member 6 by means of a pivot member 34 connecting the arm member 6 and the lever arm 32.

The slot 30 is of such dimension as to permit pivotal movement of the lever arm 32 relative to and in front of the forward face of the body 4 in such manner that one surface of the lever arm 32 is in contact with member 22.

The arm member 7 is provided with a slot 40 extending transversely therethrough and throughout the length thereof, as may be best observed by reference to Fig. 2 so that the free extremity of the lever arm, opposite from the extremity which is pivoted to the arm member 6, is receivable therein whereby the aforementioned swinging movement of the lever arm 32 is facilitated.

A spring member 44 is disposed in an opening 42 extending through the body 4 and in communication with the slot 40. This spring is seated between a set screw 46 and a detent 48 and exerts through the detent, a force against the free end of the lever arm.

A cam member 50 has a cammed end portion and a forked end 54. The cammed end portion 52 is receivable in the slot 40 of the member 7. The cammed end portion 52 is held in pivotal relation to the arm member 7 by a pin 56 whereby the cam member 50 is swingable relative to the arm member 7 and the body 4.

The outermost cam surface 53 of the cammed end portion 52 abuts the lever arm 32 and as it swings the lever arm is moved back and forth by said cam against said spring 44.

The forked end 54 of the cam member 50 receives in the provided slot a caliper finger 60 and same is held relative thereto by means of a knurled tension screw 62. The end of the finger has a radius 63 whereby the finger 60 may be swung on this pivot to any desired position and held thereto by means of the tightening of said screw 62.

The end of the arm member 6 is forked to provide a slot in which a caliper finger 70 is receivable, same being held relative thereto by means of a screw 62.

That is to say, the calipers 60 and 70 may be swung inwardly and outwardly to any desired

predetermined position and then are locked into position by the tightening of the screws 62 and 72 respectively.

The finger 70 is fixed relative to the arm member 6 whereas the finger 60 may be pivoted relative to the cam member 50.

If desired, the fingers 60 and 70 may be interchanged with outside caliper fingers 80 and 90, the same having lugs 82 and 92 respectively which are receivable in their respective slots as above pointed out. These may be locked in any desired position by means of the tightening screws 62 and 72 respectively.

In operating the device, to obtain an inside measurement, the pressure exerted on the ball pointed fingers when placed between the points to be measured, puts into operation the cam member 50 causing same to pivot on the pin 56, and by reason of the eccentricity of the cammed end to exert pressure against the lever arm 32 causing a movement of the lever arm 32, which in turn forces down the indicator contact face 22 thereby putting into operation the indicator hand in the well known manner.

The invention may be embodied in other specific forms without departing from the essential characteristics thereof. Hence, the present embodiments are therefore to be considered in all respects merely as being illustrative and not as being restrictive, the scope of the invention being indicated by the appended claim rather than by the foregoing description, and all modifications and variations as fall within the meaning and purview and range of equivalency of the appended claim are therefore intended to be embraced therein.

What it is desired to claim and secure by Letters Patent of the United States is:

A gauge including the combination of an indicator having a contact face extending outwardly therefrom, a body fixed to the indicator and having a pair of spaced fixed arms extending therefrom, a lever arm pivotally mounted on one of the fixed arms of said body at one extremity thereof and having an opposite extremity and an intermediate portion therebetween engageable with the contact face of the indicator, and a pair of caliper fingers each engageable with one of the arms of said body, one of said caliper fingers being pivotally fixed to one of the arms of said body, the other of said caliper fingers being pivotally fixed to the other of the arms of said body and having a cam surface engageable with the free extremity of said lever arm and actuating said lever arm into and out of engagement with the contact face of the indicator.

HOWARD DEWEY PETCH.
